United States Patent Office

Des. 201,002
Patented May 4, 1965

201,002

SHOE HEEL

Le Roy Hahn, 2218 Wismer St., Overland, Mo.

Filed June 2, 1964, Ser. No. 80,242

Term of patent 14 years

(Cl. D7—5)

I claim:

The ornamental design for a shoe heel, substantially as shown.
